UNITED STATES PATENT OFFICE.

HEINRICH DECHAMPS, OF CHARLOTTENBURG, GERMANY, ASSIGNOR TO GENERAL ELECTRIC COMPANY, A CORPORATION OF NEW YORK.

CYLINDER CONSTRUCTION FOR ENGINES.

1,109,204.

Specification of Letters Patent.

Patented Sept. 1, 1914.

Application filed December 23, 1913. Serial No. 308,395.

To all whom it may concern:

Be it known that I, HEINRICH DECHAMPS, a subject of the King of Prussia, residing at Charlottenburg, Germany, have invented 5 certain new and useful Improvements in Cylinder Construction for Engines, of which the following is a specification.

The present invention relates to the construction of water cooled cylinders for internal combustion engines operating on the 10 high compression plan, and especially to those having oppositely moving pistons in the same cylinder.

The object of my invention is to improve 15 and reduce the cost of construction of such cylinders, particular reference being made to the arrangement whereby objectionable distortion effects due to expansion and contraction when in operation are obviated.

20 For a consideration of what I believe to be novel and my invention, attention is directed to the accompanying description and claims appended thereto.

In the drawing is illustrated an internal 25 combustion engine in vertical section, the pistons being omitted in the interest of clearness.

1 indicates the sub-base of the engine which carries the shaft bearings and mounted thereon is the main base or crank casing 30 2, the upper wall of the latter being provided with as many openings as there are cylinders and also with a receiver or chamber 3 containing pure air to clean the cylinder or cylinders of exhaust gases and to supply the necessary air to support combustion.

4 indicates the cylinder and 5 the water jacket therefor. Midway of the cylinder is 35 a combustion chamber 6, the bore of which may, as shown, be slightly larger in diameter than the cylinder proper either to increase the cubical contents or to avoid finishing or both. The portion of the cylinder 40 adjacent the combustion chamber is provided with integral projections 7 and 8, the former being arranged to receive the fuel injector and the latter the air starting valve and its casing. These projections extend 45 through the wall of the water jacket but are separated therefrom by a small clearance 9 so that the cylinder with the projections can expand and contract without affecting the water jacket, and also so that changes in 50 shape of the jacket will not affect the cyl-

inder. When the fuel injector and air starting valves are mounted in place the clearance space 9 will, of course, be closed by a suitable packing to prevent the escape of cooling water from the jacket.

60 The upper end of the cylinder is provided with exhaust ports 10 that communicate with passages 11 leading to the outside of the jacket. The metal forming the bridges 12 between ports contains passages 13 to 65 permit the cooling water to flow from one part of the cooling chamber to the other. The metal around the passages 11 acts to tie or connect the cylinder and jacket. The upper end of the cylinder is also formed 70 with guides 14 for the cross-head of the upper piston. The lower end of the cylinder is provided with ports 15 and passages 15^a through which air from the receiver 3 enters to wash out the burned gases and 75 supply the necessary air to support combustion for the next firing stroke. The bridges between these ports are also provided with passages for cooling water. The metal around the passages 15^a acts to tie or 80 connect the cylinder and the lower end of the jacket when the latter is slotted, as will appear later. The disposition of the metal in the region of the ports is such that the cylinder is definitely centered and held in 85 place in the receiver. In a sense the scavenging and exhaust ports divide the cylinder into three parts, that part between the rows of ports being subjected to the greatest temperature.

90 The cylinder and jacket are cast as a unit and said jacket is provided with a flange 16 that rests on the top of the receiver and is attached thereto by suitable means. To prevent the ill effects due to unequal expansion 95 and contraction of the cylinder proper and the jacket, I slot the jacket as at 17 in a direction perpendicular to the axis of the cylinder. This may be done when the casting is made or by a machine operation later, 100 the latter being the somewhat better plan, especially where the slot is narrow. In any event it should be of such width, measured in the direction of the length of the cylinder, as to allow for the difference in expansion of 105 the cylinder and jacket. The slot is preferably located in line with the upper wall of the receiver which is bored to receive the cylinder. The peripheral portion of the slot 110 is enlarged to receive the packing 18, the

latter being made of rubber or some other suitable form of packing material. Being inserted between the cylinder and the surrounding wall of the receiver it will be held 5 in place without special retaining means. Owing to the slot 17 the weight of the cylinder is transmitted to the flange 16 solely through the part of the water jacket immediately above it. This arrangement permits 10 of slight relative movements of the parts to compensate for changes due to temperature effects. As before stated, the cylinder may be considered as being composed of three parts, the middle or central part containing 15 the combustion chamber and the upper and lower ends. The end portions are not so much influenced by temperature changes as is the middle part and hence it is not so important to slot the wall of the water jacket 20 around them, but it can be done if necessary or desirable. The lower end, next to the middle part, is most affected by temperature changes and I may, therefore, provide means to compensate for such changes. The metal 25 between the lower ends of the cylinder and the jacket is either cut away by a machine operation or the parts may be separated in the casting operation. Stating the matter another way, the lower end of the water 30 jacket is slotted concentric with the axis of the cylinder. In the space or slot thus formed is fixed a ring 19 that has inner and outer shoulders to receive packing rings 20 made of rubber or other suitable material 35 of a compressible nature so that unequal expansions of the cylinder and jacket can take place without opening the joints. The lower wall 21 of the receiver, in addition to being bored to receive the cylinder, is shouldered 40 to receive a compressible packing 22. By slotting the lower end of the cylinder, as shown, and providing a filling piece and packings, I avoid the use of special means 45 for holding the packings in place.

My improved arrangement has the advantage of reducing the cost of cylinders of the character described and particularly by simplifying the machine work thereon.

In accordance with the provisions of the patent statutes, I have described the principle of operation of my invention, together with the apparatus which I now consider to represent the best embodiment thereof; but I desire to have it understood that the apparatus shown is only illustrative and that 55 the invention can be carried out by other means.

What I claim as new and desire to secure by Letters Patent of the United States, is:—

1. A cylinder for an engine which is 60 formed as a unit with its cooling jacket, said jacket being slotted in a plane perpendicular to the axis of the cylinder to compensate for the effects of the different temperatures to which the cylinder and jacket are subjected.

2. A cylinder for an engine which is formed in one piece with its water jacket and is provided with scavenging and exhaust ports, said jacket being provided with 70 a cylinder supporting flange located in the plane of the middle portion of the cylinder between the ports and slotted in a plane perpendicular to the axis of the cylinder to reduce the effects of temperature changes. 75

3. A cylinder for an engine which is formed in one piece with its water jacket, said jacket being slotted in a plane perpendicular to the axis of the cylinder and also at one end concentric thereto, and filling 80 means for said slots.

4. In an engine, the combination of a support having an opening, a cylinder and water jacket formed in a unit and located in the opening, said jacket being slotted in a 85 plane perpendicular to the axis of the cylinder, and a packing that closes said slot and is located between the jacket and the wall of said opening.

In witness whereof, I have hereunto set 90 my hand this 5th day of December, 1913.

HEINRICH DECH AMPS.
